DUST MOP

Conrad Falland, Chicago, Ill.

Application March 26, 1942, Serial No. 436,352

4 Claims.

(Cl. 15—147)

The present invention relates to dust mops and the like and has to do with means for joining the mop to the head and means for joining the head to the handle.

In some dust mops pockets are provided in the upper surface of the mop and the head is inserted into the pockets to form a jointer between the head and the mop. This has not been satisfactory because the fabric has a tendency to stretch and so to loosen the jointer and because of the more or less difficult procedure involved in inserting and removing the mop.

The present invention overcomes the aforesaid objections by providing means to facilitate the insertion of the head into the pockets or its removal therefrom and means whereby the fabric is always held taut.

One object of the invention is to provide a mop head which is adapted to automatically vary its length in a manner to always hold the mop fabric taut even though the length of same may vary by stretching or shrinking.

Another object of the invention is to provide a mop head which may easily be inserted or removed from the mop pockets.

A further object of the invention is to provide a new and unique structure for joining the head to the handle and for easily changing the position of the head from the transverse to the longitudinal position with reference to the longitudinal plane of the handle.

And another object of the invention is to provide a new and unique structure for a mop head which may easily be inserted into a pocket type mop of predetermined shape and size in which the distance between the outer limits of the opposite pockets is substantially less than the maximum length of the head.

And a further object of the invention is to provide in a mop having its head pivotally connected with the handle means for limiting the rolling movement of the head about the axis of the pivot.

And an object of the invention is to provide the elements required for the indicated purposes in a form combining details and simplicity with utility in a manner to facilitate the production and assembly of parts.

Other objects will be apparent from the drawing and specifications, which set forth the unique construction, arrangement and combination of elements in the invention.

In the drawing—

Figure 1 is a side elevation of the mop; Figure 2 is a plan section on line 2—2 of Figure 1 and

with the mop in place on the head; Figure 3 is a bottom view of the mop head; Figure 4 is a plan section on line 4—4 of Figure 1, an enlarged scale. Figure 5 is a longitudinal section on line 5—5 of Figure 4; Figure 6 is a cross section on line 6—6 of Figure 4; and Figure 7 is a schematic layout of a modified construction.

In the present form of the invention, plate 1 is preferably formed of a single sheet of metal and includes a collar 2 projecting vertically from the face of the plate with its central opening continuous to the under side of the plate. A multiplicity of equally spaced apart notches 3 are formed in the face of the collar in a manner to provide pairs of oppositely disposed notches adapted to engage the hereinafter identified pivot 20, the axis of each pair of notches passing through the vertical axis of the collar 2. And channels 4, 4 and 5, 5 of plate 1 are formed by inwardly turned flanges 6, 6 and 7, 7. A U shaped loop 8 is fixed to the plate 1 at channels 4, 4, preferably by spot welding, and a U shaped loop 9 is slidably mounted in the opposite end of the plate in channels 5, 5. The free ends of arms 10, 10 of loop 8 have lugs 11, 11, and springs 12, 12 are mounted on the arms 10, 10 all as shown in Figures 1 to 6 inclusive.

And a tubular shaft 13 having a flange 14 at its lower end and a transverse opening 15 at its upper end is mounted in the aforesaid collar 2 with its lower end extending a substantial distance below the under side of the collar and its upper end extending a substantial distance above the face of the collar, and a coil spring 16 is mounted on the shaft 13 between flange 14 and the under side of the collar.

With the tubular shaft 13 in place as heretofore indicated the handle and head are connected by forcing the shaft upward to a position where its transverse opening 15 and openings 19, 19 in plates 18, 18 register at the top of collar 2 and inserting pivot 20 through said openings.

To mount loop 9 in channels 5, 5 of plate 1 force the free ends of arms 10, 10 toward each other to the position indicated by dotted lines in Figure 3 then release pressure and let the arms spring into place. Lugs 11, 11 prevent the loop from leaving the channels under the outward urge of springs 12, 12.

The handle 17 is provided with plates 18, 18 at its lower end which plates fit over the outside of collar 2, openings 19, 19 at the lower end of said plates are adapted to receive a pivot 20, and cams 21 at the lower end of said plates are positioned a substantial distance below the openings 19, 19.

The mop comprises a lower layer 22, pockets 23, 23 are formed at opposite ends of the mop by upper layers 24, 24 and thrums 25 depending from the lower layer, the distance between the outer limits of said pockets being substantially less than the maximum length of the aforesaid head.

To connect the mop and head insert loop 9 in one of the pockets 23 and force plate 1 against springs 12, 12 until the opposite pocket can be slipped over the end of loop 8. Then release pressure to let the springs urge the loops firmly into the respective pockets.

It is obvious that a mop of the character described mounted on the aforesaid head will always be held taut notwithstanding variations in its length due to stretching or shrinking. It is also obvious that a mop indicated may easily be inserted or removed by simply compressing the springs to shorten the head.

To change the transverse position of the head with reference to the axis of handle 17, tilt the handle to a near vertical position to make cams 21 engage the surface of plate 1 and lift pivot 20 from a given pair of the notches 3 of collar 2, then rotate the handle with reference to the collar until said pivot registers with another pair of the notches when spring 16 will urge the pivot and collar into locking engagement. Or,

To change the transverse position of the head with reference to the axis of the handle, hold the handle in a more or less inclined position and rotate the head about the transverse axis of the pivot 20 until the pivot registers with another pair of the notches 3 and is urged into locking engagement with the pair. The rounded form of the pivot serves as an inclined plane to lift the pivot as the collar 2 and the pivot are relatively rotated.

It is obvious from the foregoing that the head can be quickly and easily changed from the transverse or broad to the longitudinal or narrow position to meet requirements in mopping narrow or wide spaces.

As hereinbefore indicated the handle and the head are pivotally connected. Cam means 21 limit the rocking movement of the head. This combination provides desirable limited free movement of the head about the axis of the handle pivot 20, thus overcoming an objection to the conventional rigid connection between the handle and the head and the objection to unlimited free movement of the head about said axis.

It is to be noted that collar 2, tubular shaft 13

and the handle 17 in vertical position have a common vertical axis, and that the transverse axis of pivot 20 and the transverse axis of each pair of the notches 3 coincide with said common vertical axis.

It is obvious that details of the invention may be varied without departing from the spirit of the invention. One such variation is illustrated in Figure 7 in which end members 9a and 9a represent modified forms of end members 9 and 9.

I claim:

1. In a mop, a head comprising a central portion and end portions adapted to engage the ends of a mop of predetermined shape and size, 15 one of said end portions comprising a U shaped loop of predetermined form slidably mounted in the central portion, springs mounted on the arms of the loop between the outer limits of the arms and said central portion whereby the length of 20 the head may be varied by the compression or expansion of the springs under varying degrees of resistance by a given mop as aforesaid mounted on the head.

2. In a mop, a handle, a head comprising a central portion and end portions adapted to engage the ends of a mop of predetermined shape and size, 25 one of said end portions comprising a loop having parallel arms, springs mounted on the arms between the outer limits of the arms and the central portion of the head, said arms being slidably mounted in paralleling inwardly 30 facing channels on opposite sides of one end of said central portion and having limiting means at their free ends.

3. In a mop, a head comprising a central portion and end portions adapted to engage the ends of a mop of predetermined shape and size, the outer edges of one of said end portions and the outer edges of one end of said central portion 40 being associated operatively so that one of said portions is slideable over the other, and spring means whereby said end portion is urged outward from said central portion.

4. In a mop, a head comprising a central portion and end portions adapted to engage the ends of a mop of predetermined shape and size, one of said end portions being slidably mounted in paralleling channels on opposite edges of one end of said central portion, and spring means whereby said end portion is urged outward from said central portion.

CONRAD FATLAND.
